UNITED STATES PATENT OFFICE

DEZSÓ VON CSILLÉRY, OF BUDAPEST, HUNGARY

RAIL JOINT

Application filed March 6, 1930, Serial No. 433,707, and in Hungary December 17, 1929.

My invention relates to rail joints and more particularly to the joints known as scarfed joints.

It is an object of my invention to eliminate shocks as the wheels run across the joint.

To this end I provide each rail end with a plane central contact surface and in connection with this surface I provide curved surfaces extending toward the sides of the rail head.

By thus configuring the rail ends I make the gap smallest or nil in the central region of the rail where the load is a maximum, and gradually increases toward the sides of the rail head, having its maximum width at either side of the rail head.

In the drawings affixed to this specification and forming part thereof a rail joint embodying my invention is illustrated diagrammatically by way of example.

In the drawings

Fig. 1 is a plan view of the joint,

Fig. 2 is a horizontal section of the joint 25 taken on the axes of the fish bolts,

Fig. 3 is an elevation of the joint, and

Fig. 4 is a section on the line IV—IV in Fig. 3, drawn to a somewhat larger scale.

Referring to the drawings, 1 and 2 are the 30 ends of two rails forming a joint, and 3 and 4 are their respective joining faces. As will appear from Fig. 1 the joining faces are in contact in the central plane of the rail head and curves extend from the central reaches 35 of the joining faces toward the rail head the width of which increases toward the sides of the rail head. As will appear from Fig. 2 the web and the flanges of the rails are formed in conformity with the rail heads, that is, the width of the gap is a maximum at the sides of the flanges, and a minimum at the centre of the web. However, it is not necessary that the curvature of the faces should be continued throughout the rail, but as shown 45 the sides of the gaps in the flanges may extend at right angles to their edges.

In the rail head, however, it is important 50 that the curvature should extend throughout the head with the maximum width of the gap h , (Fig. 3) at the lower side of the rail

head. The width is gradually reduced until it is nil or substantially nil in the region of maximum load per unit of area. The straight central reach merges very gradually into the curves at the sides so that even where there is a distinct gap at the border regions of the maximum load per unit of area, it is quite small.

5 and 6 are the fish plates of the rails 2 and 1, respectively. These plates are of the usual type, but are welded or otherwise permanently connected with their respective rail ends in order to make up for the weakening of the web. 7 are the fish bolts which are inserted in holes 8, 10 and 9 of the fish plates and the web. The holes 9 and 10 are cylindrical but the holes 8 are extended in order to permit heat expansion. As the holes 10 in the web are cylindrical, the web is not weakened more than is absolutely necessary.

In order to reduce the steepness of the curves and to make the curves longer without unduly pointing the ends of the rails, the faces are preferably helical at the sides of the rail head.

In order to obtain a curve defined by mathematical laws the curvature of the jointing faces may be designed as a parabola of the third order. If this plane curve is fitted to the rail head the outer configuration of the jointing face will be obtained.

The length of the curve is determined by the size of the gap desired, with the tread of the wheels guided throughout the joints without shock. This condition is fulfilled if the wheels during all the phases of their movement across the joint are in contact with both rail ends, that is, if the joint is bridged also at the ends of the curved jointing faces. The proper curvature is obtained if throughout the gap, and also at its maximum width h , the sides of the rail joints have common vertical tangents t , Fig. 3, that is, such vertical tangents should always be in the plane of the lateral faces of both rail ends.

I wish it to be understood that I do not desire to be limited to the exact details of construction shown and described for obvi- 100

ous modifications will occur to a person skilled in the art.

In the claims affixed to this specification no selection of any particular modification 5 of the invention is intended to the exclusion of other modifications thereof and the right to subsequently make claim to any modification not covered by these claims is expressly reserved.

10 I claim:

1. A rail joint of the scarfed type comprising rail ends having each a central surface and curved faces extending from said central surface to the sides of the rail head, the 15 radius of said curved faces varying from said central surface toward the sides of the rail head.

2. A rail joint of the scarfed type comprising rail ends having each a central surface and curved faces extending from said central surface to the sides of the rail head, the 20 radius of said curved faces varying uniformly from said central surface toward the sides of the rail head.

25 3. A rail joint of the scarfed type comprising rail ends having each a central surface, and helical faces extending from said central surface to the sides of the rail head.

4. A rail joint of the scarfed type comprising rail ends having each a central surface, and faces shaped approximately to parabolic 30 generating curves extending from said central surface to the sides of the rail head.

35 5. A rail joint of the scarfed type comprising rail ends having each a central surface and curved faces extending from said central surface to the sides of the rail head, the radius of said curved faces varying from said central surface toward the sides of the rail 40 head, and the curves being so shaped that the ends of the rails at the sides of the rail head have common vertical tangents even at the maximum dilatation of the joint.

45 6. A rail joint of the scarfed type comprising rail ends having each a central surface and curved faces extending from said central surface to the sides and to the base of the rail head, the radius of said curved faces 50 varying from said central surface toward the sides and the base of said rail joint.

In testimony whereof I affix my signature.

DEZSÓ von CSILLERY.
